(57) **CLAIM**

The ornamental design for a sole for an overshoe, as shown and described.

DESCRIPTION

FIG. 1 is a bottom view of a sole for an overshoe showing our new design;

FIG. 2 is a left hand side view thereof;

FIG. 3 is a right hand side view thereof;

FIG. 4 is a perspective bottom view thereof;

FIG. 5 is a bottom view thereof;

FIG. 6 is a front view thereof; and,

FIG. 7 is a rear view thereof.

The broken line showing a showing an overshoe-upper throughout the views illustrates the portion of the design that forms no part of the claim.
